[57] **CLAIM**

The ornamental design for a gun rack, as shown and described.

DESCRIPTION

FIG. 1 is a front elevational view of a gun rack showing my new design;

FIG. 2 is a top plan view thereof;

FIG. 3 is a bottom plan view thereof;

FIG. 4 is a side elevational view taken from the left of FIG. 1;

FIG. 5 is a side elevational view taken from the right of FIG. 1.

The claimed design can embody multiple paired hooks in excess of those explicitly disclosed in the drawings.

FIG. 1

FIG. 2

FIG. 3

FIG. 5

FIG. 4
